UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

VARIABLE LINE SPACER FOR TYPEWRITERS.

Application filed April 7, 1919. Serial No. 287,949.

To all whom it may concern:

Be it known that I, OTTO A. HOKANSON, a citizen of the United States, residing at Woodstock, in the county of McHenry and 5 State of Illinois, have invented certain new and useful Improvements in Variable Line Spacers for Typewriters, of which the following is a specification.

This invention has for its object the provision of typewriter line spacers which shall be of improved construction and operation.

The invention is exemplified in the combination and arrangement of parts shown in the accompanying drawing, and described 15 in the following specification, and it is more particularly pointed out in the appended claims.

In the drawings—

Fig. 1 is a vertical sectional view through 20 a portion of a typewriter platen having one embodiment of my invention connected therewith; and

Fig. 2 is a transverse sectional view on line 2—2 of Fig. 1.

The numeral 10 designates the wooden core of a typewriter platen having a rubber cover 11 on its periphery and provided with a platen end 12 which centers the platen on its rod 13. The end of the platen not 25 shown in the drawing, is rigidly and detachably connected with the rod 13 in any well known manner. The platen carriage end plate 14 has a bushing 15 riveted thereto and a sleeve 16 is journaled in the bushing 15 and surrounds the platen rod 13. A hollow stem 17 engages the end of the sleeve 16 and is held fixed thereon by a set screw 18. The stem 17 is also fixed to the 30 end of the rod 13 by a set screw 19 and a hand wheel 20 is rigidly carried on the end of the stem 17.

Secured to the end of the platen 14 by wood screws 21, is a plate 22 and a second plate 23 having a circular flange 24 projecting 35 from the lateral face thereof is secured to the end plate 22 by machine screws 25. The flange 24 is provided with circumferentially arranged internal ratchet teeth 26. Journalled on the sleeve 16 and partially surrounded by the flange 24, is a ratchet hub 27 which carries a ratchet wheel 28 riveted thereto in position to lie against the outer edge of the flange 24. A circumferential flange 29 on the sleeve 16 separates the ratchet hub 27 from the bushing 40

15. An arm 30 is journaled on the bushing 15 and carries a pawl 31 pivotally mounted on its outer end in position to engage the teeth of the ratchet wheel 28. A limit stop 32 for the pawl arm 30 is carried on a plate 33 journaled on the sleeve 15, and the plate 33 is provided with a spring pressed pin 34 which may engage any one of a series of openings 35 formed in a projection 36 on the carriage end plate 14. The arm 30 which carries the pawl 31 is oscillated by a link 37 connected with a hand lever 38 which may be pivoted in any suitable manner upon the platen carriage. The ratchet wheel hub 27 is provided with 70 a pair of pawls 39 pivotally mounted at 40 on the inner face thereof and the upper ends of the pawls 39 are connected by a spring rod 41 which normally draws the pawls toward one another, as shown in Fig. 2. The 75 pawls 39 are in alignment with the ratchet teeth 26 and may be forced outwardly into engagement with the ratchet teeth by a pawl operating cone 42 slidably mounted on the sleeve 16. The cone 42 is connected with the 80 inner end of a rod 43 which is disposed in a groove 44 formed in the platen shaft 13. The outer end of the rod 43 is provided with a knob 44 by which the rod 43 and cone 42 may be slid inwardly and outwardly. When 85 the cone 42 is slid to the right, as viewed in Fig. 1, it presses outwardly on spring bars 45 which are formed integral with the pawls 39. This action of the cone 42 forces the pawls 39 into resilient engagement with the 90 ratchet teeth 26. The portion of the cone 42 which is of greatest diameter is spaced inwardly a slight distance from the end of the cone, as shown in Fig. 1, so that when the cone is moved inwardly a portion of the cone 95 of maximum diameter will pass the spring bars 45 so that the bars will engage the tapering portion of the cone at the left of the portion of greatest size. In this way the cone 42 will be automatically held in its inner position when the knob 44 has been moved inwardly. The knob 44 is threaded onto the end of the rod 43 so that it may be 100 adjusted longitudinally on the rod in order that the inner face of the knob will strike 105 the outer face of the stem 17 when the greatest diameter of the cone 42 has passed the pawls 45. The knob 44 is provided with slots 46 which are engaged by a screw 47 to hold the knob from rotation on the rod 43 110

when it has been once adjusted. A circular shoulder 48 is provided on the plate 23 to bear against the inner faces of the pawls 39 to prevent the pawls from being moved laterally by the cone 42 when it is forced inwardly by the knob 44.

It will be understood that when the pawls 39 are forced outwardly into engagement with the ratchet teeth 26, the line spacing ratchet wheel 28 will be held in fixed relation with the platen. When, however, the cone 42 is withdrawn, as shown in Fig. 1, the pawls 39 will be moved inwardly, as shown in Fig. 2, out of engagement with the ratchet teeth 26, and the platen may then be rotated by the hand wheel 20 independently of the line spacing ratchet 28. Since the teeth 26 are very fine, the platen may be rotated any very small amount for adjusting the paper, and when a proper adjustment of the paper has been obtained, the knob 40 may again be moved inwardly to connect the line spacing ratchet wheel 28 with the platen, so that the next movement of the pawl 31 will move the paper the usual amount, beginning with the position to which it has been adjusted while the platen was disconnected from the line spacing ratchet wheel.

If at any time it is desired to renew the platen, the end of the platen not shown may be disconnected from the rod 13 and the set screw 19 may be loosened to release the rod 13 from the stem 17. After this has been done, the rod 13 may be entirely withdrawn from the platen by movement to the right, and then when the pawls 39 have been released, the platen may be moved slightly to the right, when it will be entirely free from the ratchet mechanism. The only part which will remain attached to the platen is the plate 23, and if desired, this may be removed also by releasing the screws 25. This arrangement permits changing of the platen without the necessity of changing the line spacing ratchet mechanism at the same time, thus greatly reducing the cost of renewing the platen.

I claim:

1. In combination, a typewriter platen, a frame for supporting said platen, ratchet mechanism for operating said platen, a bushing carried by said frame, a sleeve journaled in said bushing, said sleeve and bushing constituting a pivotal support for said ratchet mechanism, a platen rod extending through said sleeve and removable therefrom for detachably holding said platen in operative position adjacent said ratchet mechanism and a clutch member slidably mounted on said sleeve for controlling said ratchet mechanism.

2. In combination, a typewriter platen, a frame for supporting said platen, a bushing fixed in said frame, a sleeve journaled in said bushing, a ratchet wheel journalled

on said sleeve, mechanism mounted on said bushing for operating said ratchet wheel, a platen rod extending through said sleeve for holding said platen in position adjacent said ratchet wheel, said platen rod being movable into and out of position to permit removal of said platen, pawls for connecting said platen with said ratchet wheel, clutch mechanism for operating said pawls to connect and disconnect said platen with said ratchet wheel, and a clutch rod extending longitudinally of said platen rod for operating said clutch.

3. In combination, a typewriter platen, ratchet mechanism for operating said platen, a clutch for connecting and disconnecting said platen with said ratchet mechanism, a movable cone for operating said clutch, said cone being provided with a portion of maximum diameter arranged to form an automatic lock for holding said clutch in engaging position, a stop for limiting the movement of said cone, and resilient means for engaging an inclined surface of said cone when in locked position for urging said cone to its limiting position.

4. In combination, a typewriter platen, ratchet mechanism for operating said platen, pawls for connecting said platen with said ratchet mechanism, springs connected with said pawls, means for operating on said springs to move said pawls into holding position, said operating means being provided with a portion of maximum size which is movable past the springs on said pawls for automatically locking said pawls in holding position and yieldingly holding said operating means in locking position.

5. In combination, a typewriter platen, ratchet mechanism for operating said platen, means for supporting said ratchet mechanism independently of said platen, pawls for operatively connecting said platen with said ratchet mechanism, a movable member for operating said pawls, a stop for limiting the movement of said member, and means for adjusting said stop and member relative to one another to cause said movable member to assume proper position relative to said pawls when limited by said stop.

6. In combination, a typewriter platen, ratchet mechanism for operating said platen, pawls pivotally carried by said ratchet mechanism for connecting and disconnecting said platen with said ratchet mechanism, a wedge-shaped member movable laterally relative to said pawls to force said pawls into holding position, and means on said platen for supporting said pawls against lateral movement away from their pivotal support under the influence of said wedge-shaped member.

7. In combination, a typewriter platen, ratchet mechanism for operating said platen, pawls for connecting said ratchet mechanism

with said platen, a wedge-shaped member movable laterally relative to said pawls for forcing said pawls into holding position, resilient means for transmitting pressure from said wedge-shaped member to said pawls, means for engaging lateral faces of said pawls to support said pawls against lateral movement under the pressure of said wedge-shaped member, and adjustable means for limiting the lateral movement of said wedge-shaped member, said wedge-shaped member being provided with a portion of maximum extension which moves past said resilient means for transmitting pressure to said pawls, to hold said wedge-shaped member in operating position when said member has moved to its limiting position. In testimony whereof I have signed my name to this specification on this 2nd day of April, A. D. 1919.

OTTO A. HOKANSON.
